UNITED STATES PATENT OFFICE

GEORGE H. GLADE AND GEORGE H. GLADE, JR., OF CHICAGO, ILLINOIS

SALES DEVICE

Application filed February 8, 1929. Serial No. 338,438.

This invention relates to a sales and advertising device, and particularly to a device for stimulating sales. It has for one object to provide a mechanical means for awarding periodically a bonus to a purchaser. Another object is to provide in connection with such a device a visible means for calling attention to it and an audible means for calling attention to it at the time that the bonus is awarded. Other objects will appear from time to time in the course of the specification and claims.

The invention is illustrated more or less diagrammatically in the accompanying drawings wherein:

Figure 1 is a side elevation of the device; Figure 2 is a vertical cross section taken generally on line 2—2 of Figure 1;

Figure 3 is a transverse vertical cross section taken on line 3—3 of Figure 2; Figure 4 is a horizontal cross section taken on line 4—4 of Figure 3;

Like parts are designated by like characters throughout the specification and drawings. A is a base plate.

B, B' are side members or walls. B¹ is a wall generally similar to the walls B, except that it is provided with a slot B². All the walls B, B' are provided with openings B³ within which pieces of glass or other transparent material B⁴ may be positioned. The transparent part B⁴ will normally be advertising material, that is to say, it will normally have upon it advertising matter. The same matter may be displayed in all the windows or different matter may be displayed in some of them. The glass is normally held in position by spring clips B⁵ which may be removably screwed into position by screws B⁶. Formed on the sides B, B¹ are lugs B⁷ which receive screws B⁸ by means of which the side wall members are fastened to the base plate A.

C is a dividing plate located within the enclosure formed by the side walls and supported on lugs C¹ which extend outwardly from the walls B, B¹, and screwed to the lugs by means of screws C². Supported upon the member C is a light base or socket D, within which is removably positioned a light D¹. Within the light base is positioned a

flashing mechanism of a light connection. Its details are not shown, as they form no particular part of the present invention. As a rule a flashing mechanism is thus used and the light is automatically flashed off and on. This is not an essential part of the invention, but is generally used.

E is a bell, normally of a convenient type. It is positioned on the member C. Current is supplied to it by wires E¹, E². The wire E¹ is connected to a transformer E³ which may be grounded on the casing when the casing is made of metal, which is generally the case. The other wire E² is fastened to a contact member E⁴ which is supported on an insulated part E⁵ which is itself carried on a bracket E⁶ supported from the base plate A.

Supported also from the bracket E⁶ is a sleeve F. In one end the sleeve bears against the upstanding part of the bracket E⁶ and at its other end it has a reduced portion F¹ and upon this reduced portion is movably mounted a ratchet F². F³ is a washer or spacing ring abutting against the reduced portion F¹ of the sleeve F. F⁴ is a supporting plate held in position against the washer F³ by means of a screw F⁵. F⁶ is a lever pivoted upon the member F⁴ extending outwardly through the slot B² in the plate B¹ and having a key part F⁷ at its outer end. F⁸ is a ratchet pawl pivoted on the lever F⁶ and provided with a ratchet engaging point F⁹ adapted to engage the ratchet F². F¹⁰ is a spring fastened at one end to the lever F⁶ and at its other end to the parts C. It tends normally to hold the lever and its associated pawl in an upward position as shown in full lines in Figure 2. F¹¹ is a spring fastened to the bottom plate A and bearing against the ratchet F² to prevent over-running or excessive movement.

G is a spring contact member mounted on the ratchet F² and adapted, once during each rotation of the ratchet, to contact the contact member E⁴. When this occurs the bell circuit is completed through the ground and the bell will be rung. More than one contact member might be mounted on the ratchet.

H, H' are lamp connections and H¹ is a

switch. It will be noticed that the lamp connections and wires are spliced to the lead wires H², H² which are connected to the transformer.

5 I is a dome or cover for the casing. It may be of metal or any suitable substance, or it may be transparent or opaque. In particular, any part of the casing may be made transparent. This may be for advertising or 10 other purposes. The transparent window B⁴ may be made larger. The dome or cover I may be transparent and may be used for advertising purposes. In short, practically any part of the casing may be used for advertising purposes and practically any part 15 of the casing may be made transparent.

It will be realized that while we have shown and described an operative device, many changes might be made in the size, shape, 20 number, relation and distribution of parts without departing materially from the spirit of our invention and we wish our showing to be considered in a large measure dia-grammatic.

25 The use and operation of this invention are as follows:

The device is susceptible of many uses. One of the more important uses is in connection with the sales of articles. When so used 30 the device may be placed upon the cashier's desk. The purchase having been made, the purchaser moves to the cashier's desk with a check to be paid. Upon presentation of the check the purchaser depresses the lever once, 35 causing the ratchet to advance one or more notches. The amount which the ratchet is advanced with each depression of the lever depends on the setting of the parts. Periodically the bell connection will be completed 40 and the bell rung. When this happens a prize may be given to the purchaser, the pur- 45 chaser may be free or any other bonus ar- 50 arrangement may be adopted.

When the device is used as an advertising 45 device in addition to its use as a bonus awarding machine, the advertising material is in some way mounted upon or formed in the device. It may be upon a transparent portion 55 of the casing or it may merely be upon a non-transparent portion. It is sufficient where the device is intended to act as an advertising medium that some part of the device contain advertising material. When this is done, the device will of course serve as an advertise- 60 ment. If a flashing light is used, that will serve additionally to call attention to the advertising. If the audible signal is used that will serve still further to call attention to the device carrying the advertising.

65 One effective form of advertising is to have the light flash constantly and to provide advertising on the windows B⁴. Thus the device itself automatically attracts attention by reason of the flashing light and anyone looking 70 at the device will have his attention called

to the advertising upon it whether this be on the transparent window B⁴, the dome I or any other part of the device.

Since every purchaser will operate the machine in order to see whether or not he is to get a bonus, he will of necessity look at the device and will have his attention called to the advertising upon it. In addition to this, whenever the device gives an audible signal to indicate that a bonus has been paid to a 75 purchaser, people in the neighborhood of the machine and elsewhere hearing the noise will turn to see who has gotten the bonus and therefore will have their attention called to the device itself. In this fashion, everyone 80 purchasing articles in a store equipped with this bonus and advertising device will be com- 85 pelled to look at the device at least once when he operates it and will also have his atten- 90 tion called to the device at other times by reason of the flashing light and the audible 95 signal when a bonus is awarded to some other purchaser.

We claim:

1. In combination in a sales device, a 100 customer operated signal, and means for operating said signal, including a manually operated mechanism, said mechanism including a signal operating part and means for advancing it in a step by step movement, said 105 signal operating part carrying means to operate the signal only occasionally when it is operated.

2. In combination in a sales device, a 110 customer operated electric signal, a contact connecting mechanism for operating said signal, including a manually operated member, 115 said mechanism provided with a contact member and means for moving it, said means shaped to complete the contact only occasionally in response to operation of the manually operated member.

3. In combination in a sales device, an automatically operated visible signal and a customer operated electric audible signal, a contact connecting mechanism for operating said signal, including a manually operated member, 120 said mechanism provided with a contact member and means for moving it each time said manually operated member is moved, 125 said moving means shaped to complete the contact only occasionally.

4. In combination in a sales device, means for giving an intermittent, automatically controlled, visible signal, and an occasional manually controlled audible signal, said means including an electric light and an automatic flashing mechanism therefor, and a bell and a manually controlled circuit mechanism therefor said last mentioned mechanism including a contact member, a carrier therefor, means for moving said carrier in a step by step movement, whereby the contact is periodically completed.

5. In combination in a sales device, a cus- 130

5 tomer controlled audible signaling mechanism, including an audible signal and means for occasionally operating it, said means including a manually controlled operating member adapted to be operated by the customer, said means adapted to operate the audible signal only occasionally in response to such manual operation said last mentioned mechanism including a contact member, a 10 carrier therefor, means for moving said carrier in a step by step movement, whereby the contact is periodically completed.

6. In combination with an advertising device carrying visible advertising matter, 15 means for calling attention to said advertising matter including a visible signal and a second signal, a mechanism for operating said second signal adapted to be operated by each customer, said mechanism adapted to 20 operate the second signal periodically at a predetermined time in its cycle of operation in response to said customer operation.

7. In combination with an advertising device carrying visible advertising matter, 25 means for calling attention to said advertising matter including a visible signal and an audible signal, a mechanism for operating said second signal adapted to be operated by each customer, said mechanism adapted to 30 operate the audible signal periodically at a predetermined time in its cycle of operation in response to said customer operation.

8. In combination with an advertising device carrying visible advertising matter, 35 means for calling attention to said advertising matter including a flashing visible signal and a second signal, a mechanism for operating said second signal adapted to be operated by each customer, said mechanism adapted to 40 operate the second signal periodically at a predetermined time in its cycle of operation in response to said customer operation.

9. In combination with an advertising device carrying visible advertising matter, 45 means for calling attention to said advertising matter including a flashing visible signal and an audible signal, a mechanism for operating said second signal adapted to be operated by each customer, said mechanism adapted to operate the audible signal periodically at a predetermined time in its cycle of operation in response to said customer operation.

50 10. In a sales device, a light source, an audible signal and a positive customer operated means for actuating said signal, said signal actuating means including a member adapted to be manipulated by the customer and having associated with it a signal operating part, the actuating means being so shaped that the operating part is progressively brought into and out of operating position.

55 11. In combination in a sales device, a vis-

ible signal, an audible electric signal and customer operated means for periodically operating said audible signal, said means including a switch, an operating part for said switch and means for progressively moving said part in a step by step movement into and out of operating position to operate the switch. 70

12. In combination in a sales device, a visible signal, an audible electric signal and customer operated means for periodically actuating said audible signal, said means including a carrier, a fixed contact member and the contact member on said carrier, and customer operated means adapted to move said carrier, whereby, in response to the movement of the carrier, said movable contact is progressively moved toward said fixed contact in a step by step movement. 75

Signed at Chicago, in the county of Cook 80 and State of Illinois, this 6th day of February, 1929.
